FLARE

Charles H. Vanderlaan, Larchmont, N. Y., assignor to Radio Patents Corporation, New York, N. Y., a corporation of New York

Application April 23, 1946, Serial No. 664,344

3 Claims. (Cl. 67—55)

1

This application is a continuation in part of my abandoned application Serial No. 532,278, filed April 22, 1944.

The present invention relates to flares, lamps, evaporators and similar devices comprising a container or vessel filled with a suitable liquid such as fuel oil, etc., and a wick to carry the fuel or liquid to the point of combustion or evaporation by capillary action.

In the known devices of this character, such as kerosene lamps, lanterns, flares, heating appliances, etc., a wick of cotton or similar fabric material is used which has many disadvantages and shortcomings giving rise to numerous defects and deficiencies. In the first place, a wick or liquid feeding member of this type is subject to constant deterioration, requiring frequent trimming and replacements. It furthermore causes clogging, uneven burning of the flame if not constantly adjusted and regulated, as well as smudging and other well known defects.

Accordingly, an object of the present invention is to provide a device of this character which is substantially devoid of the above-mentioned drawbacks and defects; which is simple and cheap to manufacture; which practically requires no or little attention during use, and which will insure a uniform liquid or fuel feed or discharge within a practically unlimited life.

With these objects in view, the invention involves generally the use of a unitary fuel container or vessel and a wick or fuel feeding member of porous material, such as porcelain or other ceramic materials, the pores or interstices of which are of a suitable size or diameter to feed or carry a desired liquid to the point of combustion or evaporation by capillary action substantially without deterioration or impairment of its efficiency during operation.

The invention will be further understood from the following detailed description of a few practical embodiments thereof taken in reference to the accompanying drawing forming part of this specification, and wherein:

Figure 1 is a cross-section of a lamp or flare constructed in accordance with the invention; and

Figure 2 is a similar view illustrating a modification of the invention.

Referring to Figure 1, there is shown a unitary fuel container and permanent wick member consisting of porcelain, ceramic or equivalent porous material and comprising a container portion or vessel 10 and a central rod or wick 11 extending into said vessel and projecting outwardly there-

2

from to provide a burner or evaporating member 12. Vessel 10 is provided with a suitable filling hole liquid-tightly closed by a threaded tap screw 14 or any other suitable closure device. The outer surface of the vessel 10 excepting the surface of the burner or evaporator 12 is glazed or otherwise treated or coated with liquid-impervious material, as indicated by the dotted line 13, whereby to prevent exudation or evaporation of liquid from surfaces other than said burner or evaporator. The porosity of the material is suitably chosen so that a given liquid such as kerosene or other fuel in the vessel will be carried or fed to the exposed surface of the burner 12 by capillary action.

If desired, the inside surface of the vessel 10 excepting the wick 11 may similarly be glazed or coated with liquid-impervious material to prevent undue absorption of fuel. Alternatively, if the inner surface is left uncoated, the wick portion 11 may be omitted, in which case sufficient fuel or other liquid is absorbed by the vessel walls and fed to the burner or evaporator 12. In this manner, the construction of the device is still further simplified.

Referring to the modified construction shown in Figure 2, wherein like reference numbers identify like parts as shown in Figure 1, the vessel 10 is surrounded by an enclosure 15 of a shock-absorbing material such as cork, felt, etc., secured thereto by gluing or in any other suitable manner such as by means of metal bands as shown at 16. There are furthermore shown in Figure 2 means for regulating or controlling the brightness or size of the flame if the device is used as a lamp, flare, heater or the like. For this purpose, there is shown a cylindrical metal sleeve 17 secured to the lower portion of the burner 12 by a screw thread or the like. A further cylindrical sleeve 18 having an inwardly threaded lower portion engaging suitable outer threads of the sleeve 17 may be raised or lowered by rotating it by the aid of a knob 20 in such a manner that the upper portion 19 spaced by a suitable distance from the burner or wick 11 and provided with draft or vent holes, will act as a regulator to control the size or brightness of the flame in a manner readily understood. If desirable, means may be provided as shown at 21 in Figure 2 for detachably securing a transparent or translucent globe or cylinder enclosing the flame in a manner customary with known kerosene lamps and lanterns.

The liquid vessel may be of any desired size and shape and preferably consists of porous ceramic or an equivalent material.

There is thus provided by the invention a device suitable for various uses or applications as a lamp, flare, evaporator for improving the air in rooms, outdoor heating appliance as used in orchards, etc., which has a practically unlimited life, requires little or no attention, and is substantially devoid of the disadvantages and shortcomings inherent in known devices of this type using a wick of fibrous material as a liquid carrying or feeding element.

While I have shown and described a few desirable embodiments of the invention, it is understood that this disclosure is for the purpose of illustration and that various changes in shape, proportion and arrangement of parts, as well as the substitution of equivalent elements and materials for those herein described may be made without departing from the spirit and scope of the invention as defined in the appended claims. The specification and drawing are accordingly to be regarded in an illustrative rather than a limiting sense.

I claim:

1. A device of the character described comprising a vessel of porous material, a wick of the same material integral with said vessel and extending outwardly therefrom to present a desired evaporating surface area, said material having a porosity suitable to cause a liquid in said vessel to be fed to said evaporating area by capillary action, and a liquid-impervious coating covering the outside surface of said vessel and wick excepting said evaporating area.

2. A device of the character described comprising a vessel of porous material, a wick of the same material integral with said vessel and extending from the inside to the outside of said vessel to present a desired evaporating surface area, said material having a porosity suitable to cause a liquid in said vessel to be fed to said evaporating area by capillary action, and a liquid-impervious coating covering the outside surface of said vessel and wick excepting said evaporating area.

3. A lamp comprising a vessel of porous refractory material, a wick of the same material integral with said vessel and extending outwardly therefrom to form a burner having a desired evaporating surface area, said material having a porosity suitable to cause a combustible liquid fuel in said vessel to be fed to said burner by capillary action, and a protective coating covering the outside surface of said vessel and burner to prevent exudation of liquid therefrom excepting said evaporating area.
